UNITED STATES PATENT OFFICE.

BENJAMIN KOVACS, OF NEW BRUNSWICK, NEW JERSEY.

DOOR LOCK.

Application filed February 24, 1927. Serial No. 170,539.

The present invention relates to improvements in door locks, and more particularly to locks of that type wherein the locking bolt is controlled by two sets of tumblers, each set of tumblers being operated by a separate key:

One of the objects of the invention is to generally simplify the construction of locks of this type, and to so design the escutcheon plate thereof that the keyhole for receiving one of the keys is concealed and has the general appearance of a single keyhole lock escutcheon plate.

Another object of the invention is to combine with the lock an electric alarm in such a manner that a bell is set in action when the locking bolt of the lock is retracted from its locking position.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is an elevation of the outer face of a door, showing the improved lock in position thereon; Fig. 2 is an elevation of the inner face of the door with the lock in position thereon; Fig. 3 is an elevation of the lock with the bolt projected and the cap plate removed, to show the interior parts; Fig. 4 is also an elevation of the lock, the cap plate being attached thereto; Fig. 5 is a section taken on line 5—5 of Fig. 3, the cap plate being in position on the lock; Fig. 6 is an elevation of one of the keyhole linings; Fig. 7 is a diagram of the electric circuit of the alarm feature of the lock; Fig. 8 is an elevation of a keeper co-operating with the locking bolt; and Fig. 9 is a section taken on line 9—9 of Fig. 8.

In the drawings, the numeral 10 indicates a lock casing and the numeral 11 the cover plate thereof. In the casing are formed holes 12, through which extend screws 13, for attaching the said casing to the inner face of a

door 14. In the lock casing is slidably disposed a locking bolt 15, guided in its movement by an opening 16 in the face plate 17 of the said casing and by a ledge 18 in the casing. With the locking bolt cooperates a spring-pressed tumbler 19, that is pivoted at 20 to the lock casing and provided with lugs 21, adapted to cooperate with notches 22 in the upper edge of the bolt. The tumbler is provided with a projection 23, for a purpose hereinafter to be described. In the lower edge of the locking bolt are provided two notches 24, into which the bit of a key enters when it is desired to project the bolt into locking position or to retract the same from such position. The said key may be inserted into the lock both from the outside and from the inside. For this purpose the casing and the cap plate are provided with registering keyholes 25 and 26, respectively. The keyhole 26 is surrounded by a keyhole lining 27, which is riveted or otherwise attached to the cap plate and is, preferably, made of two sections 28 and 29, which are adjustably secured together by a screw 30. This adjustment is necessary in order to accommodate the said keyhole lining to doors of varying thicknesses. The keyhole lining is disposed within a keyhole 31 in the door, the said keyhole registering with the holes 25 and 26 above-mentioned.

The tumbler 19 has made integral therewith a downwardly extending projection 32, which is disposed in the path of the key, so that the lugs 21 may be disengaged from the notches 22 in the locking bolt, to permit the said bolt to be shifted into locking and retracted positions, as the case may be.

On the locking bolt is formed an arm 33, provided on its free end with a pin 34, adapted to enter slots 35 in a set of spring-pressed tumblers 36, which are pivoted at 37 to the lock casing. The slots 35 are out of alignment with the said pin when the locking bolt is in its projected position, shown in Fig. 3 of the drawings, and in such case the said set of tumblers rests upon a stop 38 within the lock casing. The tumblers 36 are actuated by a key, entering the said casing from the outside through a keyhole 39 in the cap plate 11, said keyhole being provided with a lining 40 of the type above described and disposed in a keyhole 41 in the door. The two keys are of different configurations, that is to say they are not interchangeable. Therefore, in order to

unlock the door, two keys are necessary. The key co-operating with the keyhole 39 is so designed that, upon giving the same one-half of a revolution, the tumblers 36 are lifted 5 around their pivot 37 to bring the slots 35 thereof into alignment with the pin 34 on the arm 33 of the locking bolt.

For the purpose of lifting the tumblers 36 from the inside, a lever 42 is pivoted at 43 to 10 the outer face of the lock casing. To this lever is fixed a pin 44, extending through a slot 45 into the lock casing and being adapted to co-operate with projections 46 on the tumblers 36, as clearly shown in Fig. 3 of the drawings. The pin 44 is disposed in the path of the projection 23 of the tumbler 19, (see Fig. 3).

The lever 42 is made of metal and is in electric contact with the metallic lock casing. 20 The said lever is provided outside of the lock casing with a metallic knob 47, preferably a frustum of a cone, adapted to co-operate with a metallic contact member 48, hinged to a base plate 49, the latter being mounted upon but 25 insulated from the lock casing. Normally the contact member 48 and the knob 47 are out of contact, as shown in Fig. 5 of the drawings. The said contact member and knob are included in an electric circuit 50, containing 30 a battery 51 and a bell 52. The wire leading from one terminal of the battery, and denoted in Figs. 3 and 4 of the drawings by the numeral 53, is in electric contact with the lock casing, while the wire leading from one of the 35 terminals of the bell, and denoted in Figs. 3 and 4 of the drawings by the numeral 54, is in electric contact with the base plate 49.

To the outer surface of the door is attached an escutcheon plate 55 of any suitable configuration and design. This escutcheon plate is provided with two key-holes 56 and 57, the keyhole 56 registering with the keyholes 25 and 26, and the keyhole 57 being in alignment with the keyhole 39. The keyhole 57 is normally covered by a slide 58, pivoted at 59 to 40 said escutcheon plate. This slide is so shaped and designed that it merges into the design of the escutcheon plate, so that persons not familiar with the lock would have the impression that it is operable by a single key only, that is to say by a key insertable through the 45 visible keyhole 56 in the escutcheon plate.

With the locking bolt co-operates a keeper 60, shown in Figs. 8 and 9 of the drawings. 55 This keeper is fastened by screws 61 to the door jamb 62 and is made of two elements 63 and 64, adjustably secured together by screws 65. These elements are so constructed that a slot 66 is formed within the same, into which 60 the locking bolt above referred to is adapted to enter. The width of this slot may be widened by unscrewing the screws 65 from the element 63 and moving the element 64 outwards. In order to keep the elements in adjusted positions, shims may be inserted be-

tween the said two elements. It is obvious that, while herein a keeper of special design has been described, any other may be used without departing from the invention, which lies mainly in the lock construction above described. 70

The operation of the improved lock is as follows: Let us assume that the locking bolt is in its projected position and the other elements of the lock are in the positions shown 75 in the several figures of the drawings. In order to retract the locking bolt from the outside, first the slide 58 must be shifted so as to uncover the keyhole 57. A key is then inserted into the said keyhole and given one-half of a turn so as to lift the tumblers 36 to bring the slots 35 therein into alignment with the pin 34 on the arm 33 of the locking bolt. A second key is then inserted into the key-hole 56. The first half of a turn of this key causes disengagement of the tumbler 19 from the locking bolt 15, and a continued movement of the key retracts partly the locking bolt from the keeper, the pin 34 entering the slots 35 in the tumblers 36. The tumbler 19 drops back into notches in the locking bolt 15, but is disengaged from these notches during the second turn of the key, so that the locking bolt may be entirely withdrawn from the keeper. As the tumbler 19 is raised, its projection 23 engages the pin 44 of the arm 42 and raises the said arm, thereby bringing its knob 47 into electric contact with the contact member 48. The electric circuit is thereby closed and an alarm sounded. A person being inside of the room may retract the locking bolt by lifting the arm 42, whereby its pin 44 comes in contact with the projections 46 on the tumblers 36, so that the slots 35 therein are brought into alignment with the pin 34. A key is then inserted through the key-hole 25 and the lock operated in the manner above described. Of course, in such case the alarm need not be operated. In order to prevent sounding of the alarm, the contact member 48 is swung around its hinge onto the base plate 49. 95 100 105 110 115

If a person attempts to pick the lock by means of a key or other instrument inserted through the keyhole 26, it is obvious that the locking bolt cannot be retracted because its pin 34 is brought into abutment with the projections 46 on the tumblers 36. 120

For the purpose of projecting the locking bolt 15, only that key is necessary which co-operates with the said locking bolt, the tumblers 36 being forced by the spring co-operating therewith into their lower positions, shown in Fig. 3 of the drawings, as soon as 125 the pin 34 is disengaged from the slots 35 in the tumblers 36.

What I claim is:

In a lock, the combination with a casing, of a locking bolt slidable therein, a tumbler co-operating with said bolt, an arm pivoted 130

to said casing provided with a pin in the path of said tumbler, a metallic contact member fixed to said arm, a second metallic contact member normally disengaged from said 5 first-mentioned contact member mounted upon and insulated from said casing, said contact members forming part of an electric circuit, the contact member on said arm being shifted into contact with said second-men-
tioned contact member when said tumbler is

actuated for the purpose of disengaging the same from said locking bolt, said second-mentioned contact member being hinged to said casing so as to permit the same to be shifted out of the path of said first-mentioned contact member. 15

Signed at New York, in the county of New York and State of New York, this 29th day of January, A. D. 1927.

BENJAMIN KOVACS.
